(57) CLAIM

The ornamental design for a banner holder, as shown and described.

DESCRIPTION

FIG. 1 is a perspective view of a banner holder showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a left side view of the banner holder shown in an extended position.

The broken line portion of the figure drawings is included to show portions of the article that form no part of the claimed design.

1 Claim, 5 Drawing Sheets(56)
